WELL CLEANER

Melvin Miller and Leon N. Davis, Flushing, Mich.

Application July 11, 1939, Serial No. 283,893

8 Claims. (Cl. 166—18)

This invention relates to well cleaners or scrapers of that general class shown and described in United States Letters Patent issued to us jointly on May 9, 1939, under No. 2,157,493, the present application being for an improvement thereon.

The object of the invention is generally to improve and simplify the construction of the cleaner so as to increase its durability and efficiency as well as to reduce the cost of production.

10 A further object is to provide novel means for mounting the scraper arms and holding said arms in operative and inoperative positions.

15 A further object is to provide a well cleaner or scraper including a tubular body portion having a sleeve or housing slidably mounted thereon and which serves to hold the arms of the scraper assembly in closed or retracted position when lowering the device into a well, and further to provide superposed coiled springs surrounding the tubular body and normally exerting a downward yieldable pressure on the scraper arm assembly and housing respectively, said springs being alternately under tension and compression according to the position of said scraper arms.

20 25 A further object is to provide the lower end of the tubular body portion with an enlarged head or spreader which contacts the free ends of the scraper arms and forces said arms laterally into engagement with the well casing under the influence of the arm assembly spring when the housing is released.

30 35 A still further object of the invention is to provide the angular terminals of the scraper arms with inclined reinforcing webs which allow the scraper teeth to slide over joints in the pipe being cleaned.

Further objects and advantages will appear in the following specification, in which similar numerals of reference indicate corresponding parts in all the figures of the drawings.

40 In the drawings:

Figure 1 is a vertical sectional view of a well scraper or cleaner embodying the present invention showing the scraper arms in closed or retracted position and the device ready to be lowered into a well.

Figure 2 is a front elevation.

Figure 3 is a vertical sectional view showing the scraper arms in extended or operative position, 50 and

Figure 4 is an enlarged vertical sectional view of the scraper arm unit or assembly.

In carrying the invention into effect, we provide a solid coupler head 5 having its upper end threaded at 6 for attachment to a correspondingly

threaded stem or, if desired, to an operating cable and its lower end reduced to form a depending shank 7. Loosely mounted on the shank 7 is a collar 8, and rigidly secured to the shank beneath the collar is a smaller collar 9 which serves to receive and sustain the weight of the operating parts of the device when lowering said device into or removing the device from the well. The shank 7 and rigid collar 9 thus form, in effect, a swivel joint, and interposed between the rubbing surfaces of the collars 8 and 9 is a flat washer 10, as shown. Rigidly secured to the collar 8 is a depending sleeve 11, the lower end of which is welded or otherwise secured to a tubular member or body portion 12. The body portion 12 is provided with oppositely disposed registering slots 13, and the lower end of said body portion is preferably reduced at 14 and is provided with a substantially globular terminal head 15 constituting a spreader member. Slidably mounted on the 20 tubular member 12 is a cylindrical housing 16, said housing being centered with respect to the reduced cylindrical portion 14 by means of an annular spacing member 17 which latter is secured to the housing 16 but is free to slide therewith on the tubular member, as will be more fully explained hereinafter. Extending through the housing 16 and spacing member 17 is a transverse pin 18 which operates within the slots 13 and serves to guide the housing 16 in its vertical movement. Fitting within the reduced extension 14 of the tubular member 12 is a rod or plunger 19, the lower end of which projects below the spreader member or head 15 while the upper end thereof is provided with a transverse opening 20 through which the pin 18 passes so as to cause the housing and plunger 19 to move in unison.

Slidably mounted on the cylindrical portion 14 is a scraper arm assembly, said assembly comprising a retaining collar 21 having a series of radial openings 22 formed therein and adapted to receive the angular terminals 23 of depending scraper arms 24. The metal constituting the retaining collar 21 is cut-away immediately below each opening 22 to form an outwardly inclined wall 25 so as to permit lateral swinging movement of the arms 24 when the latter are moved to extended position into engagement with the wall of a well. The angular terminals of the arms 24 are retained within the openings 22 by means of a locking sleeve 26 which has a tight fit with the retaining collar 21 but is free to slide on the extension 14. It will thus be seen that the upper ends of the scraper arms 24 are pivotally connected with the retaining collar so as to permit 55

said arms to be swung laterally from a vertical plane outwardly to the dotted line position shown in Figure 4 of the drawings, while at the same time the retaining ring and its associated parts 5 are free to slide vertically on the extension 14 of the body portion 12. The locking sleeve 26 not only serves to retain the pivoted ends of the 10 scraper arms in position on the retaining collar but by removing the sleeve 26 the several parts 15 may be readily disassembled when it is necessary to effect any necessary repairs thereto. The lower ends of the arms 24 are provided with lateral scraping fingers 27 having sharpened teeth 28 adapted to bite into paraffin or other deposits on 20 the well casing for the purpose of removing the same when the device is lowered into a well. The scraping fingers 27 of the arms 24 are connected by reinforcing webs 29 which allow the teeth 28 to slide over joints in the pipe being cleaned.

20 Interposed between the retaining collar 21 and an offset portion 30 on the tubular member 12 is a coiled spring 31, the purpose of which is to force the scraper arms 24 downwardly in contact 25 with the spreader head 15 and thus cause said arms to assume the position shown in Figure 3 of the drawings. A coiled spring 32 surrounds the tubular member 12 with one end thereof bearing against the sleeve 11 and the other end thereof against the spacing ring 17, said spring serving 30 to normally and yieldably hold the housing 16 in lowered position over the spreader arms and, therefore, prevent movement of said spreader arms when the device is lowered into a well. It 35 will here be noted that one of the coiled springs is always under tension while the other is under compression.

In operation, the device is lowered into a well until the end of the plunger or rod 19 strikes the bottom thereof. When this occurs, the upper 40 end of the plunger 19, by engagement with the pin 18, will force the housing 16 upwardly against the tension of the spring 32 so as to release the arms 24. As soon as the arms 24 are released, the coiled spring 31 will press downwardly on the retaining collar 21 and force the lower ends of the 45 scraper arms 24 in contact with the spreader head 15, thereby spreading the active ends of the scraper arms laterally in contact with the adjacent wall of the well to be cleaned, as best shown in Figure 3 of the drawings. When the device is 50 elevated or partially elevated, the lower end of the rod 19 will clear the bottom of the well, thereby relieving pressure on the pin 20 and causing the spring 32 to return the housing 16 to a position over the scraper arms 24 and thus hold said 55 scraper arms in closed or inoperative position during withdrawal of the device from the well. It will thus be seen that, when the plunger 19 strikes the bottom of the well, the housing 16 will 60 be forced upwardly contracting the spring 32 and permitting the spring 31 to expand to force the lower ends of the scraper arms 24 into engagement with the head 15 so as to move said arms laterally to operative position and that, 65 when the lower end of the rod 19 is elevated above the bottom of the well, the spring 32 will expand and force the housing 16 downwardly to hold the scraper arms in inoperative position and at the same time the spring 31 will be contracted and 70 held in contracted position until the housing 16 is again released. The outer surface of the housing 16 is formed with a plurality of spaced vertical ribs 33 which act as guides and serve to prevent the housing from scraping the sides of the 75 well.

From the foregoing description, it is thought that the construction and operation of the device will be readily understood by those skilled in the art and further description thereof is deemed unnecessary.

Having thus described the invention, what is claimed as new is:

1. A well cleaner comprising a tubular member, a scraper assembly slidably mounted on said member and including pivotally mounted laterally movable scraper elements, a plunger operating within the tubular member, a housing connected with the plunger for holding the scraper elements in closed position, a spreader disposed in the path of the scraper elements, and springs 10 surrounding the tubular member and bearing against the housing and scraper assembly respectively for exerting a downward yieldable pressure thereon.

2. A well cleaner comprising a tubular member, a scraper assembly mounted on said member and including laterally movable scraper elements, a plunger operating within the tubular member, a housing connected with the plunger and slidably mounted on the tubular member for holding 25 the scraper elements in closed position, a spreader carried by the tubular member for contact with the scraper elements, and coiled springs surrounding the tubular member and bearing against the housing and scraper assembly respectively for exerting a downward yieldable pressure thereon, one of said springs being held under compression while the other is under tension.

3. A well cleaner comprising a tubular member, 35 a scraper assembly mounted on said member and including laterally movable scraper elements, a plunger operating within the tubular member, a housing operatively connected with the plunger for holding the scraper elements in closed position, a spreader carried by the tubular member and disposed in the path of the scraper elements, and alternately acting coiled springs surrounding the tubular member and bearing against the housing and scraper assembly respectively. 45

4. A well cleaner comprising a tubular member, a scraper assembly slidably mounted on said member and including a retaining ring having lateral openings therein and provided with inclined walls communicating with the openings, 50 scraper arms having their upper ends formed with angular terminals seated in said openings and their lower ends provided with angular toothed portions, a plunger operating within the tubular member, a housing connected with the plunger for holding the scraper arms in closed position, a spreader disposed in the path of the scraper arms for forcing said arms laterally, and coiled springs surrounding the tubular member and bearing against the housing and retaining collar respectively. 60

5. A well cleaner including a tubular member, a scraper assembly slidably mounted on said member and including a retaining collar having radial openings therein and provided with cut-away portions communicating with said openings and defining outwardly inclined walls, scraper arms having their upper portions provided with angular terminals seated in said openings and their lower ends formed with lateral toothed extensions, inclined reinforcing webs connecting the toothed extensions and adjacent portions of the scraper arms, a locking sleeve rigidly secured to the retaining collar and movable therewith, said collar serving to hold the angular terminals of 75

the scraper arms within said openings, a plunger operating within the tubular member, a housing connected with the plunger for holding the scraper arms in closed position, a spreader, and springs bearing against the housing and scraper assembly respectively for exerting a downward yieldable pressure thereon.

6. A well cleaner including a coupling having means for attachment to a suspension element and provided with a depending shank, a collar loosely mounted on the shank, a sleeve secured to and depending from the collar, a stop collar secured to the lower end of the shank, a tubular member secured to the sleeve and provided with oppositely disposed slots, a plunger disposed within the tubular member, a housing slidably mounted on the tubular member, a spacing ring interposed between the housing and tubular member, a pin carried by the housing and extending through the spacing member and said plunger, a scraper assembly slidably mounted on the tubular member and including depending scraper arms pivotally mounted for lateral movement, a spreader disposed in the path of said arms, and coiled springs surrounding the tubular member and bearing against the spacing ring and said scraper assembly respectively for exerting a downward yieldable pressure thereon.

7. A well cleaner comprising a tubular member having oppositely disposed slots formed therein and provided with a reduced cylindrical extension, a spreader head on the lower end of said extension, a plunger extending through the tubular extension, a housing slidably mounted on the tubular member, a spacing ring interposed between the tubular member and said housing, a transverse pin extending through the adjacent end of the plunger and slots in the tubular member for engagement with the housing and spacing ring re-

spectively, a scraper assembly slidably mounted on the reduced cylindrical portion of the tubular member and including pivotally mounted scraper arms, a coiled spring surrounding the tubular member and bearing against the spacing ring, and a second coiled spring bearing against the scraper assembly and the adjacent portion of the tubular member, one of said springs being under tension while the other is under compression and serving to normally exert a downward yieldable pressure on the adjacent parts.

8. A well cleaner including a tubular member having a reduced cylindrical extension, a scraper assembly slidably mounted on said reduced extension and including a retaining ring having cut-radiating openings therein and provided with cut-away portions having outwardly inclined walls communicating with said openings, scraper arms having their upper portions pivotally mounted in said openings and their lower portions formed with scraping elements, a locking ring for retaining the upper ends of the scraping arms within the openings, said locking ring having a snug fit with the retaining collar but free to slide on the cylindrical extension of the tubular member, a spreader secured to the lower end of said extension, a plunger operating within the tubular member, a housing slidably mounted on the tubular member and operatively connected with the plunger, and coiled springs bearing against the housing and scraper assembly respectively, one of said springs being under tension while the other is under compression and both of said springs serving to normally exert a downward yieldable pressure on said housing and scraper assembly.
